Primary Examiner — Catherine R Oliver-Garcia

(57) **CLAIM**

The ornamental design for a fishing tackle, as shown and described.

DESCRIPTION

1. Fishing tackle
2. Fishing tackle
3. Fishing tackle

Designs 1 and 2 are for a fishing tackle, which consists of the tackle body with branch hollow supports formed in multiple directions, C-shaped tube supports attachable/detachable to the tackle body for lengthening the branch supports, and end caps attachable/detachable to the end of the branch supports or C-shaped tube support for preventing the fishing line from being separated or detached; designs 1 and 2 apply the principle of the structure of a pair of scales to make it leveled in the center of gravity of the weight (sinker) connected to the lower center of the tackle body, etc.; the plural fishing hooks are spaced by a certain distance horizontally; the fishing hooks and the branch fishing lines are connected through the hollow supports and C-shaped tube supports; design 3 is a fishing tackle, which consists of the tackle body with hollow support formed in one direction, C-shaped tube support, and an end cap as in designs 1 or 2; design 3 applies the principle of a lever to make it leveled in the center of gravity of the weight (sinker) connected to the lower center of the tackle body, etc.; the fishing line, the fishing hook, and the branch fishing line are connected through the hollow support and C-shaped tube support; reproductions **1.8**, **2.8**, and **3.8** are exploded perspective views of the tackle body, C-shaped tube support, and end cap of the design; reproductions **1.9**, **2.9**, and **3.9** are enlarged perspective views of the tackle body; reproductions **1.10**, **2.10**, and **3.10** are enlarged perspective views of C-shaped tube support; reproductions **1.11**, **2.11**, and **3.11** are enlarged perspective views

of the end cap; reproductions **1.12** and **2.12** are reference views of the state of use in which a weight(sinker) and fishing lines, etc., are combined to the design; reproduction **3.12** is a reference view of the state of use in which a weight(sinker) and a fishing net to attract fish are combined to the design; reproductions **1.13**, **2.13**, and **3.13** are reference views of the state diagram in which a plurality of designs are connected and form no part of the claimed designs; reproductions **1.14**, **2.14**, and **3.14** are reference views of the state diagram of a buoyancy float attached; reproductions **1.15** and **2.15** are reference views of the state diagram of fishing net to attract fish attached; reproductions **1.16**, **2.16**, and **3.15** are reference views of the state in which fish, fishing line, and the tip of fishing rod are in line and the fishing hook and the branch fishing line move together when a fish is caught.
